CLAIM

The ornamental design for a female catheter, as shown and described.

DESCRIPTION

FIG. 1 is a front, top, right-side perspective view of a female catheter showing the new design thereof;

FIG. 2 is a rear, top, left-side perspective view thereof;

FIG. 3 is a right-side view thereof;

FIG. 4 is a left-side view thereof;

FIG. 5 is a top view thereof;

FIG. 6 is a bottom view thereof;

FIG. 7 is a front view thereof;

FIG. 8 is a rear view thereof;

FIG. 9 is a front, bottom, left-side perspective view thereof; and,

FIG. 10 is a rear, top, left-side perspective view thereof.

The broken lines in the drawings illustrate portions of female catheter and form no part of the claimed design.

1 Claim, 4 Drawing Sheets
